UNITED STATES PATENT OFFICE.

ERIC H. MICELSON AND ERIC K. SKONBERG, OF BROOKLYN, NEW YORK.

LIQUID-DISPENSING DEVICE.

Application filed October 2, 1926. Serial No. 139,098.

This invention relates to a device for dispensing liquids and has for an object to provide means for dispensing a predetermined quantity of a liquid drink. 5 Another object is to provide a means for holding and storing a quantity of a hot or cold liquid in a manner to maintain a substantially constant temperature, in combination with means to dispense measured 10 quantities of said liquid, said means being located substantially entirely within said holding means.

Another object is to provide a measuring device located within a main reservoir and 15 having inlet and outlet valves and means operable in unison with said valves for venting said device to facilitate flow of liquid therefrom.

A further object is to provide a liquid 20 dispensing device comprising a valve operating lever in combination with a coin controlled lock for said operating lever.

A further object is to provide a coin controlled dispensing device which is simple in 25 construction, efficient in operation and economical to manufacture.

Other objects will appear from the detailed description which follows.

In the drawings,—

30 Figure 1 shows a side elevation of the device partly in section;

Fig. 2 is a view in section of the measuring device and related parts;

Figs. 3 and 4 show the co-operating valve 35 ports in the inlet valve plate and measuring container;

Figs. 5 and 6 show two different positions of the outlet valve and operating lever;

Fig. 7 shows the coin controlled locking 40 lever in three working positions; and

Fig. 8 shows the main operating handle in two operating positions together with the rotatable supporting block for said handle.

Referring to the drawings, numeral 1 indicates a main reservoir or liquid container 45 which is preferably a thermos jug properly constructed to maintain the confined liquid at a constant temperature for a reasonable period. Said reservoir is supported in an inverted position on a frame comprising a ring 2, legs 3, and base 4. A platform 5 carried by legs 3 supports a coin controlled locking mechanism which will be described in detail hereinafter.

55 As best shown in Fig. 2 the usual screw cap 6 of the container 1 supports all of the

elements which comprise the means for measuring and feeding predetermined quantities of the liquid. A disk like supporting base 7 made of brass or other non-corroding material and having a downwardly extending tubular extension 8 is arranged in said cap and an opening 9 is provided in said cap to receive the extension 8. A gasket 10 is placed between base 7 and cap 6. A measuring 60 container 11 preferably in the form of a common jelly glass is supported on base 7 in an inverted position. Outwardly extending lugs 12 on container 11 engage angular flanges 13 which are rigid with base 7 and thereby hold container 11 firmly against the base 7. A gasket 14 is arranged between the container and the base and another gasket 15 is arranged between flanges 13 and the circular edge 16 of the neck opening in container 1. 75

The bottom 17 of glass container 11 is ground to a true surface and drilled in three places to provide a central orifice 19, a vent opening 21 and a liquid inlet 20. A valve 80 plate 18 is rotatably mounted on the bottom surface 17 and is provided with a small square opening 22, a small opening 23 and a larger opening 24 equal in diameter to the inlet 20. A vent tube 25 is mounted on 85 plate 18 above and in line with opening 23.

A valve operating rod in the form of a tube 26 is arranged axially in container 11 and passes through opening 19. The upper end of tube 26 terminates in a square end 27 which engages the square opening 22 in valve plate 18 thereby to rotate the same. The square end 27 is threaded for a short distance to engage corresponding threads of a vent tube 28. The vent tubes 25 and 28 are 90 braced at their upper ends by a connection 31. A washer 30 and a spring 29 surround the square end 27 and act to press plate 18 against surface 17.

The lower end of rod 26 is threaded at 32 100 to engage firmly with a tapered valve 33 rotatably mounted in extension 8. A liquid outlet 34 in valve 33 is arranged to discharge in a certain position into a delivery tube 35 which extends from the extension 8. 105 An operating lever 36 is mounted at the lower end of rod 26 being held thereon rigidly by a nut 37. The free end of lever 36 is provided with a pair of spaced depending lugs 38 for a purpose to be explained later. 110 When lever 36 is rotated back and forth, rod 26, valves 33 and 18 and vent tubes 25,

28 rotate as a unit to alternately fill and empty container 11.

The means for releasably locking the liquid delivery control lever 36 will now be described. A cylindrical supporting block 39 is rotatably mounted at the center of the platform 5 and said block carries an operating lever or bar 41 extending outwardly a sufficient distance beyond a leg 3 to be grasped by the hand of an operator. A coil spring 40 is anchored one end on platform 5 and after being wound for about a one-fourth turn around a slot 40' in block 39 has its other end anchored thereto. The purpose of spring 40 is to maintain bar 41 against a leg or stop 3 and return said bar to that initial position after a clockwise rotation.

A coin controlled locking lever 43 is pivoted on a standard 44 and a depending lug 45 is formed on one end of lever 43 of sufficient weight to rotate the lever clockwise to a horizontal position until said lug contacts the platform 5. In this position, a detent 46 on lever 43 engages bar 41 to lock the same from clockwise rotation. A coin tray 48 on the free end of lever 43 is adapted to receive a coin from the usual coin chute 49. A coin stopping plate 48' is mounted on block 39 and in one position lies close to tray 48. A coin deposited in tray 48 is sufficient to overbalance lever 43 and cause a counter-clockwise rotation until the rear end of lever 43 is raised far enough upwardly to strike a vane 42 extending laterally from the operating bar 41. In this position, lever 43 has not rotated sufficiently to drop the coin from tray 48 but has rotated far enough to unlock bar 41.

It will be noted that the pair of lugs 38 depending from lever 36 are positioned to straddle the bar 41. Hence, as best seen in Figs. 1 and 2, when bar 41 is rotated clockwise from its unlocked position it will cause a similar rotation of lever 36 and its connected valves to permit of liquid delivery to outlet tube 35. When bar 41 has moved with its integral vane 42 a sufficient distance to permit said vane to clear from locking lever 43, said lever will be permitted to rotate counter-clockwise far enough to allow the coin in tray 48 to slide therefrom and into a suitable receptacle.

In the operation of the device, during the time that bar 41 is locked the openings 24 and 20 in the valve plate 18 and bottom 17 respectively are in registration and the container 11 is filled with liquid from the main reservoir 1 and, during this filling act, air from container 11 is vented through opening 21 in bottom 17 which registers with vent tube 25.

A suitable coin deposited in chute 49 and falling in tray 48 will rotate locking lever 43 counter-clockwise until stopped by vane

42 in which position bar 41 is unlocked. The outer end of bar 41 may be grasped by the operator and rotated forwardly during which time lever 36 and rod 26 rotate to shift valve plate 18 into such a position that 70 vent tube 25 will register with the opening 20 in the bottom 17 of container 11 at which time the outlet 34 in lower valve 33 will open into tube 35 to permit delivery of the liquid contents of container 11. 75

While liquid is flowing from container 11 to completely empty the same, air flows into container 11 from vent tube 25 and an equal amount of air is permitted to flow into reservoir 1 through the hollow rods 26 and 28. 80 Upon release of the handle 41, spring 40 will cause an opposite rotation of all of the parts mentioned that have been shifted to operate valve plate 18. Bar 41 is returned to its initial position against leg 3 and is 85 again locked by detent 46.

Having thus fully described our invention, what we claim as new and desire to secure by Letters Patent, is:—

1. In a liquid dispensing device, a thermally insulated liquid reservoir, a closure member therefor, means for supporting said reservoir in an inverted position, a liquid measuring device mounted on said closure member, valve means for filling said container from the reservoir, means to operate said valve means, comprising a tubular member extending from said valve means upwardly to a point above the liquid level and downwardly to a point below said closure to 100 provide a vent for said reservoir. 90

2. In a liquid dispensing device, a liquid reservoir, means to support said reservoir in an inverted position, a cap for closing said reservoir, a liquid measuring container supported interiorly of said reservoir upon said cap, a combined inlet and vent valve mounted at the upper end of said container and means exterior to said reservoir for selectively moving said valve to a position to 105 admit fluid to said container or to a position to vent air to said container. 105

3. In a liquid dispensing device, a liquid reservoir, a liquid measuring container located within said reservoir, means to fill 115 said container with liquid from said reservoir, means to close communication from said reservoir to said container and means to discharge liquid from said container as a measured quantity, said filling and discharging means comprising valves at opposite ends of said container and a tubular operating member for said valves opening at one end to the atmosphere and at the other end at a point above the liquid in 120 said reservoir to provide a vent. 120

4. In a liquid dispensing device, a main fluid reservoir, a measuring container located within said reservoir, an inlet valve at the upper end of said container, an out- 125 130

let valve adjacent the lower end of said container and an air vent for said container and means to simultaneously close said upper valve open said air vent and 5 open said lower valve, whereby to completely empty said container of its contents.

5. A liquid dispensing device comprising a thermos container supported in an inverted position, a closure cap for said container, a supporting plate on said cap, a cup-like measuring container supported on said plate in an inverted position interiorly of said thermos container, means to fill said measuring container with liquid from said 10 thermos container, means to discharge the contents of said measuring container to a point exterior to said thermos container and means to vent air to said containers.

6. In a liquid dispensing device, a main 20 fluid reservoir, a measuring container located within said reservoir, an inlet opening in one end of said container, a valve

plate rotatably mounted on said container end and having an opening adapted to register with the opening in said container end, 25 an operating rod extending through said container end and engaging said valve plate, and means to operate said rod from a point exterior to said reservoir.

7. In a liquid dispensing device, a fluid 30 reservoir, a closure cap for said reservoir, a supporting plate mounted on said cap, a liquid measuring container mounted on said plate and interiorly of said reservoir, an inlet valve on said container, an outlet valve 35 for said container mounted on said plate, means connecting said valves for operation in unison, and means to operate said connecting means.

In testimony whereof we affix our signatures.

ERIC H. MICKELSON.

ERIC K. SKONBERG.
